(57) **CLAIM**

The ornamental design for a counter for games, as shown and described.

DESCRIPTION

1. Counter for games

1.1 : Front

1.2 : Left

1.3 : Back

1.4 : Top

1.5 : Bottom

1.6 : Perspective

1.7 : Perspective

1.8 : Perspective

1.9 : Left

1.10 : Left

Left and right-side views are mirror images thereof.

The evenly spaced broken line showing is included for the purpose of illustrating portions of the "article" and forms no part of the claimed design. Portions of the counter for games are shown with symbolic breaks, formed by dash-dot-dash broken lines. The appearance of any portion of the article between the break lines forms no part of the claimed design.
